METHOD OF PRODUCING AN END THICKENING IN TUBULAR BODIES MADE BY ROLLING WITH SKEW ROLLS

Heinrich Esser, Hilden, Germany

**Application April 24, 1933, Serial No. 667,724
In Germany May 2, 1932**

3 Claims. (Cl. 80—62)

The forming of a thickening of the wall at the end of tubes is of great importance for the connection of the tubes with one another and cannot be effected conveniently by the tube manufacturing methods usually employed. Hitherto a thickening at the end has usually been produced subsequently on the smooth tube through the end of the cut-off tube being heated and upset in a die with a mandrel of suitable shape. As in this method it is necessary for the tube to be repeatedly strongly heated, much time is required and high costs are involved. For this reason it is sought to produce the end thickening in one operation with the rolling of the tubes, whereby considerable economic advantages are obtained.

In the case of tubes which are finish-rolled by the pilgering method, it has been proposed, for instance for making an internal thickening of the wall at one end, to draw in the hollow body, coming from the piercing rolls at one end by pressing or the like and to roll down this end over an offset mandrel. This method cannot, however, be employed in the case of tubes made by rolling with skew rolls. In skew roll rolling mills with a mandrel stressed in compression, that is to say in rolling mills in which the tube is rolled on to the mandrel shaft, it has already been proposed to pass the tube, after it has been rolled, without the mandrel through the rolls.

Skew roll rolling mills are also known, in which by reducing the diameter and the wall thickness of the hollow body tubes which are ready for use are produced, in which however, in contradistinction to the usual rolling mills, the mandrel is so fixed on the mandrel bar that the latter is stressed in tension, so that the tube is rolled down off the mandrel bar.

40 In order to produce an end thickening in such
skew roll rolling mills in a simple manner, ac-
cording to the invention the hollow piece coming
from the piercing rolls is drawn in at its end in
such a manner by upsetting it at the end or by
forging it in two or more part dies or the like
45 that, when introduced into the rolls, the constric-
tion will bear against the forward end of the man-
drel. The part of the hollow body projecting
beyond the mandrel is then seized by the rolls, one
the mandrel being forced between the latter and
50 is reduced without mandrel pressure, that is to
say, without reducing the wall thickness, to the
external finished diameter of the tube. On the
point of the mandrel engaging during the fur-
ther forward motion of the mandrel, the wall
55 of the hollow bloom commences to be rolled down

in such a manner that according to the calibration of the mandrel a gradual compression of the thickened cylindrical part to the part of the tube having a wall of normal thickness is produced.

In the accompanying drawing

Fig. 1 shows a skew roll rolling mill of the known kind, in longitudinal section, the figure representing the moment in which the blank which is drawn in at the end is just being introduced with the mandrel between the rolls.

Fig. 2 shows the same rolling mill, the tube being positioned between the rolls with the mandrel in the normal position, while the rolled down thickened end has left the rolls.

According to the invention the hollow bodies 3 coming from the piercing rolls pass, as they travel to the reducing skew rolls, a press or a hammer (not shown), where, by upsetting it at the end or forging it in a die, the constriction 4 (Fig. 1) at one end is produced. As the hollow body leaves the piercing rolls at a sufficiently high temperature and the operation of drawing it in can be carried out in a few seconds, there is no serious loss of heat and the hollow body can be passed directly after being forged to the skew rolls.

In the rolls 5 the withdrawn mandrel 6 is pushed into the blank, until the mandrel head 7 bears against the constriction 4. On the mandrel 6 being pushed further forward the hollow body 4 is pushed between the rolls until the blank is seized by the rolls 8 (Fig. 1). The constriction 4 will then bear against the forward end 7 of the mandrel and is reduced by the rolls without the mandrel being forced forward to the external finished diameter of the tube, the thickening 9 (Fig. 2) being thus produced. The mandrel then moves forward into the final rolling position (Fig. 2), the part 10 adjoining the thickening 9 gradually widening, corresponding to the forward motion of the mandrel, to the internal diameter of the finished tube. It is possible to determine the quantity of material in the thickened end by the length and the shape imparted to the constricted part of the hollow body and it is also possible to influence this quantity by the shape of the mandrel end.

What I claim is:

1. A method of producing a thickening of the wall at the end of tubular bodies made by means of skew rolls coacting with a mandrel, consisting in piercing the end of the blank, constricting the said pierced end in such a manner that, on the blank being introduced between the rolls, the constricted end will bear against the forward end of 55

the mandrel and be reduced by the rolls without any forward pressure being exerted by the mandrel and thereupon finish-rolling the blank.

2. A method of producing a thickening at the 5 end of tubular bodies, as claimed in claim 1, in which the quantity of material in the end thickening to be formed by rolling is determined by the shape given to the constricted end of the pierced part of the blank and the shape of the 10 mandrel end.

3. A method of rolling out a tube with an internally thickened end from a tubular blank in

a skew roll rolling mill, using a mandrel, consisting in drawing the tubular blank in at its end in such a manner that the drawn in part will bear against and project beyond the forward end of the mandrel when the blank is introduced into the rolls, rolling down the part of the blank projecting beyond the forward end of the mandrel and reducing its external diameter to the desired extent without mandrel pressure, and then rolling down the wall of the blank between the rolls and 10 the mandrel. 5
